UNITED STATES PATENT OFFICE

ELMER C. SWANSON, OF LARCHWOOD, IOWA

BUCKLE

Application filed September 16, 1930. Serial No. 482,319.

This invention relates to a buckle particularly adapted to be worn in connection with ladies' shoes, hats and the like, although the same may be used for any purpose for which a conventional buckle is applicable.

The primary object of the invention is to provide, in a manner as hereinafter set forth, a buckle by means of which two straps, ribbons or the like may be secured together without the extension of any portion of the buckle through the straps or ribbons, and which may be tightened or loosened at will simply by turning the buckle.

A further object of the invention is to provide a buckle of the character aforesaid which includes a projection adapted to be grasped for the purpose of turning the buckle and positioned in a manner to prevent any interference with the straps when the buckle is rotated.

A further object of the invention is to provide a buckle of the character aforesaid which will present a novel and attractive appearance.

With the foregoing and other objects in view, the invention consists of the novel construction, combination and arrangement of parts as hereinafter more particularly described, and as illustrated in the accompanying drawings wherein is shown an embodiment of the invention, but it is to be understood that the description and drawings are to be taken as illustrative and that the invention is intended to be limited only by the scope of the claims hereunto appended.

In the accompanying drawings in which like numerals are employed to designate like parts throughout the several views:

Figure 1 is a plan of a buckle in accordance with this invention showing a pair of straps associated therewith, the buckle being adjusted to loosely connect the straps.

Figure 2 is a view similar to Figure 1 showing the buckle adjusted to tighten the straps.

Figure 3 is a section taken on the line 3-3 of Figure 2.

Figure 4 is a view similar to Figure 1 showing the buckle adjusted to partially tighten the straps.

Referring to the drawings in detail, the numeral 1 indicates generally the body portion of my improved buckle, such body portion preferably being in the form of a polygonal plate. Opening through the peripheral face of the plate 1, in spaced relation to each other, are a pair of slits 2 and 3 which extend in parallel, spaced relation. An inner end portion 4' of the slit 3 extends beyond and curves around the inner end of the slit 2 whereby the inner end of the slit 3 is oppositely disposed with respect to the inner end of the slit 2. The space between the slits 2 and 3 provide a tongue 4 having its outer end free and in flush relation to the peripheral face of the plate 1. The tongue 4 includes an outer end portion 5, an intermediate portion 6 arranged substantially at a right angle to the portion 5, an intermediate portion 7 arranged substantially at a right angle to the portion 6, and an inner end portion 8 disposed in parallel relation to the portion 7. The tongue 4 is adapted to be inserted through a loop 9 formed on a strap 10, the strap 10 extending upwardly through the slit 2 and having a return end portion 11 adapted for extension downwardly through the slit 3 whereby the loop 9 is formed. The return portion 11 is secured to the strap 10 by some suitable means such as a staple 12 with the securing means arranged in a manner to present an unbroken surface on the outer face of the portion 11.

In parallel relation to the inner end portion of the slit 3, the plate 1 is formed with an arcuate slot 13 having its end walls substantially in alignment with the inner end wall of the slit 3 transversely of the plate 1. The space between the slot 13 and slit 3 provides an arcuate tongue 14 which includes end portions 15 and 16 and an intermediate portion 17, the intermediate portion 17 being arranged at substantially a right angle to the portions 15 and 16. Owing to the formation of the tongue 14, the ends thereof are anchored to the plate 1. The tongue 14 is adapted to support a loop 18 on a strap 19 extending in an opposite direction from the strap 10. The strap 19 extends upwardly through the slot 13 and is provided with a

returned end portion 21 which extends downwardly through the slit 3 and is secured to the strap 19 by some suitable means such as a rivet 22. Adjacent the periphery of the 5 plate 1, and further adjacent one end of the slot 13, the plate is provided on its upper face with an upwardly extending projection 23 which may be grasped by the fingers for the purpose of rotating the plate relative to the 10 straps 10 and 19.

10 In assembling the straps and plate, the loop 18 is extended around the end portion 6 of the tongue 14, and the loop 9 is extended around the end portion 5 of the tongue 4. 15 Upon rotation of the plate 1 in the direction indicated by the arrow in Figure 1, the tongues 14 and 4 are slidably extended through the loops 18 and 9 respectively. Upon sliding the tongues 14 and 4 through 20 the loops 18 and 9, the straps 10 and 19 are drawn toward each other, the straps being shown at the limit of their inward movement in Figure 2, and substantially midway the length of their inward movement in Figure 4. It is to be understood that the rotation of the plate 1 may be stopped at any 25 point desired in order to bring the straps 10 and 19 into the desired relationship. As the straps are drawn taut by the rotation of the 30 plate, the straps are drawn into frictional engagement with the lower face of the plate whereby the plate is held in any position to which the same is turned.

It is thought that the many advantages of 35 a buckle in accordance with this invention will be readily apparent, and although the preferred embodiment of the invention is as illustrated and described, it is to be understood that changes in the size, shape and arrangement of parts may be resorted to, so long as such changes fall within the scope of 40 the invention as defined in the appended claims.

What I claim is:—

45 1. A buckle comprising, a plate formed with a pair of spaced, arcuate slits opening through the periphery thereof and providing therebetween an arcuate tongue having a free end adapted to be inserted through a looped strap, said plate further being formed with a slot in spaced relation to one of said slits and coacting therewith to provide an arcuate tongue anchored at its ends and adapted to extend through a looped strap oppositely disposed with respect to the first mentioned strap, said plate being rotatable to slide the tongues relative to the straps for drawing the latter towards each other.

50 2. A buckle comprising, a plate formed with a pair of spaced, arcuate slits opening through the periphery thereof and providing therebetween an arcuate tongue having a free end adapted to be inserted through a looped strap, said plate further being formed with a slot in spaced relation to one of said

slits and coacting therewith to provide an arcuate tongue anchored at its ends and adapted to extend through a looped strap oppositely disposed with respect to the first mentioned strap, said plate being rotatable to slide the tongues relative to the straps for drawing the latter towards each other, and an offset projection adjacent the periphery of the plate for rotating the latter.

55 3. A buckle comprising, a plate formed with a pair of spaced, arcuate slits opening through the periphery thereof and providing therebetween an arcuate tongue having a free end adapted to be inserted through a looped strap, said plate further being formed with a slot in spaced relation to one of said slits and coacting therewith to provide an arcuate tongue anchored at its ends and adapted to extend through a looped strap oppositely disposed with respect to the first mentioned 60 strap, said plate being rotatable to slide the tongue relative to the straps for drawing the latter towards each other, each of said tongues including a plurality of longitudinal portions extending substantially at right angles to each other.

4. A buckle comprising, a polygonal plate formed with a pair of spaced, arcuate slits opening through the periphery thereof and providing therebetween an arcuate tongue having a free end, a strap extending upwardly through one of said slits and having a returned end portion extending downwardly through the other of said slits to provide a loop extending around said tongue, said plate being formed with an arcuate slot in spaced relation to one of said slits and coacting therewith to provide an arcuate tongue anchored at its ends, a strap extending upwardly through said slot and having a returned end portion extending downwardly through one of said slits to provide a loop extending around the arcuate tongue which is anchored at its ends, said plate being rotatable to slide the tongues relative to the straps for drawing the latter towards each other, and a projection on the upper face of the plate for rotating the latter.

5. A buckle comprising, a polygonal plate formed with a pair of spaced, arcuate slits opening through the periphery thereof and providing therebetween an arcuate tongue having a free end, a strap extending upwardly through one of said slits and having a returned end portion extending downwardly through the other of said slits to provide a loop extending around said tongue, said plate being formed with an arcuate slot in spaced relation to one of said slits and coacting therewith to provide an arcuate tongue anchored at its ends, a strap extending upwardly through said slot and having a returned end portion extending downwardly through one of said slits to provide a loop extending around the arcuate tongue which is anchored 115

at its ends, said plate being rotatable to slide the tongues relative to the straps for drawing the latter towards each other, and a projection on the upper face of the plate for rotating the latter, each of said tongues including a plurality of longitudinal portions disposed at substantially right angles to each other.

5 In testimony whereof, I affix my signature hereto.

ELMER C. SWANSON.
